(57) **CLAIM**

The ornamental design for a microfluidic device as shown and described.

DESCRIPTION

FIG. 1 is a perspective view of a microfluidic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,

FIG. 9 is a referential view demonstrating the usage condition of our new design.

The broken lines in the drawings depict environmental subject matter and form no part of the claimed design.

1 Claim, 9 Drawing Sheets
